UNITED STATES PATENT OFFICE

1,994,642

ILLUMINATED SIGN

Louis Patton Hamilton, Cheltenham, Pa.

Application October 19, 1933, Serial No. 694,211

3 Claims. (Cl. 40—133)

The object of the invention is to provide improvements in illuminated signs and display media generally, but more especially in a novel construction and arrangement, whereby an infinite number of multiple effects may be obtained by employing both direct and diffused lighting of a relatively opaque medium, so cut as to provide silhouette and the cut-out regions being partially or entirely spanned by clear or colored transparent media, adapted to alter the color of the light rays shining thru said regions.

Another object is to provide an improved and simplified hollow frame within which a particular display card is positioned, in addition to the one or more sources of illumination, the means to flash said illumination sources, and if desired one or more switches to control said sources.

A further object is to provide in such a device, provision for a plurality of electric lamps, as representative of any suitable and available light source, and if desired each of such lamps being of a different color, and a correspondingly different time for flashing and period of duration, so that with a given opaque card having cut-out regions and a semi-transparent covering for said regions of a given color, and the matter carried by the card having a given appearance when illuminated from the front alone, the different colors of the lamps will combine with the color of the said semi-transparent medium, to provide still further effects or appearances.

With these objects of the invention thus broadly stated, said invention comprises further details of construction and operation, as are hereinafter fully brought out in the following description, when read in conjunction with the accompanying drawings, in which

Fig. 1 is a front elevational view of a device comprising one embodiment of the invention;

Fig. 2 is a right side elevational view of the same;

Fig. 3 is a front elevational view of the device with the forward cover or closure removed, and a fragmentary portion of the interior removed; and

Fig. 4 is a vertical section on the line 4—4 of Fig. 3, but with the lamp on top and the flashing mechanism shown in elevation.

Referring to the drawings a box-like structure is provided, comprising a rear wall 1, end walls 2, top wall 3, and a bottom wall 4, said last-named wall being adapted to be hung or to rest upon any suitable supporting surface 5, thru the medium of rubber or other types of cushions or the like 6. Said box-like structure is formed in

any suitable manner, and the edge portions of its several walls may overlap by means of flanges 7, or in fact any other arrangement which will insure maximum rigidity and minimum weight and expense.

Extending peripherally around the interior of this box-like structure is a frame comprising in cross section an L-shaped angular member, comprising forwardly positioned flanges 8, lying in a common plane and rearwardly extending flanges 10 5, which latter are secured directly to said top, bottom and side walls, as shown in Fig. 4. Beyond this frame and the rear wall 1, any desired number of lamps 10 are provided the same being secured in any suitable manner to the side walls 15 2, or in fact to the top and bottom walls as well, if desired. The heat from these lamps is adapted to pass outwardly from said box-like structure, thru spaced apertures 11 in the upper portion of the rear wall 1, said apertures, however, being spanned at a slight distance by means of a diagonally extending plate 12 also having spaced apertures 13, which tho are not in alignment with said first-mentioned apertures, thereby preventing light rays from the lamps 10 20 25 passing outwardly from said structure. Also suitably positioned within said structure is a suitable make-and-break or flasher mechanism 14, of any well-known type, the same being connected, if desired, thru a suitable switch 15 with said lamps 10, so that the lamps blink simultaneously, or go on and off alternately, for a purpose hereinafter described.

At this point it should also be noted that, as before indicated, a plurality of make-and-break 35 mechanisms may be present, and connected to different lamps, which lamps may be of different colors, in order to give different visual effects to the display sign hereinafter described. For the purpose of illustration, a display sign is here 40 shown as comprising an opaque field 16, having cutout regions 17, providing silhouette, letters, figures, or in fact any desired indicia, said cut-out regions being spanned in whole or in part by means of transparent media 18 of a single or 45 multiplicity of colors, and it is thru this semi-transparent media that the rays of one or more of said lamps shine when they are properly energized.

In addition thereto, a suitable combined bracket, shield and reflector 19 is secured to the outer surface of the top wall 3, or to another convenient portion of said box-like structure, in such a position that the rays of a lamp 20 therein shine constantly upon the outermost surface of 50 55

the opaque field 16 of the display card. As a result, said field with its color and other characteristics is constantly illuminated and therefore productive of a given characteristic effect, 5 while the effect of the same is changed instantly upon the energizing of one or more of the lamps 10, since the illumination of the semi-transparent media 18 from the rear is thereby emphasized by comparison with the less brilliantly illuminated field 16 of the display sign.

The display sign as a unit when in operative position rests against the flanges 8, and is normally secured in this position by means of a diagonally, inwardly extending flange 21, comprising a frame-like structure hinged at 22 to the forward edge portion of the bottom wall 4. Surrounding said flange 21 said frame may comprise a planular section 23, while the inner edge portion of said last-named flange is preferably 20 turned outwardly to provide a planular flange 24, which bears substantially uniformly against the outer surface of said display card, in order to maintain the same in operative position.

With this construction, the same frame-like structure while normally retained in closed position by friction or latch engagement 25 with the top wall 3, may be oscillated outwardly upon the hinge 22, so as to permit a ready withdrawal and replacement of the display sign cards. During such operation, it will be evident that the bracket 19 and lamp 20 are in no wise affected, since they are permanently positioned outside of and free from the path of movement of said box-like structure, which in the end serves to 35 form a partial closure for said box-like structure hereinbefore first described.

I am aware that the invention may be embodied in other specific forms without departing from the spirit or essential attributes thereof, 40 and I therefore desire the present embodiment to be considered in all respects as illustrative and not restrictive, reference being had to the accompanying claims rather than to the foregoing description to indicate the scope of the invention.

Having thus described my invention what I claim and desire to protect by Letters Patent of the United States is:—

1. The combination of a box-like structure having an open face, a source of light within said structure, a peripheral flange within said

structure intermediate its forward and rear extremities, a relatively opaque display card provided with light-passing regions, and positioned directly in front of said light source, a closure for a portion of said open face hinged to the forward edge portion of said structure and forming a frame for said card, an inwardly directed peripheral flange carried by said closure and having only an edge portion normally bearing against and maintaining said card against said first flange, and a second source of light outside of said structure and so arranged laterally of said card as to direct its rays upon and substantially in the plane of the outer surface of said card. 10

2. The combination of a box-like structure, having an open face and providing a peripheral flange forming a continuation of the side walls of said structure, an inwardly extending substantially planular peripheral flange within said structure, intermediate its forward and rear extremities, a relatively opaque display card provided with light-passing regions normally positioned against said second flange, and a closure for said open face hinged to the forward edge portion of said flange, and comprising a diagonally inwardly projecting peripheral flange, 15 normally positioned within and protected by said first flange and having only its inner free edge portion bearing against the outer surface of said card. 20

3. The combination of a box-like structure, having an open face and providing a peripheral flange forming a continuation of the side walls of said structure, an inwardly extending substantially planular peripheral flange within said structure, intermediate its forward and rear extremities, a relatively opaque display card provided with light-passing regions normally positioned against said second flange, a closure for 25 said open face hinged to the forward edge portion of said first flange, and comprising a diagonally inwardly projecting peripheral flange, normally positioned within and protected by said first flange and having only its inner free edge portion bearing against the outer surface of said 30 card, a source of light directly to the rear of said card, and a second source of light positioned outside of said structure, laterally of and operative to cast its rays only at highly acute angles across the outer face of said card. 35
